Atty.

UNITED STATES PATENT OFFICE

HARVEY J. DIVEKEY, OF AURORA, ILLINOIS

TATTOO MARKER

Application filed October 3, 1928. Serial No. 310,090.

My invention relates to tattoo markers and is particularly adapted to tattooing initials or other identification marks on poultry, rabbits, foxes, cattle, swine, sheep, dogs, and other animals, and one of the objects of the invention is the provision of an improved and simplified structure for such purpose.

Another object of the invention is the provision of a tattoo marker in the form of a hand stamp.

Another object of the invention is the provision of improved tattoo points which will penetrate the outside layers of the skin without blemishing the flesh and therefore without injuring the birds or animals.

Another object of the invention is the provision of a tattoo marker in which the tattoo points are rigidly connected to a single handle to facilitate operation of the marker and to provide a single rigid structure having no relatively movable parts so that the marker will not become broken or come apart and therefore its tendency to get out of order by long continued use will be reduced to a minimum.

A further object of the invention is the provision of a resilient pad or cushion through which the tattoo points project and beyond which they extend, which pad or cushion shall be impervious to the tattoo ink so as not to absorb the same, but to hold and collect such ink for transfer to the tattoo points upon operation of the tattoo marker.

Other objects of the invention will appear hereinafter, the novel features and combinations being set forth in the appended claims.

In the accompanying drawings—

Fig. 1 is a sectional elevational view showing my improved tattoo marker approximately twice its actual size; and

Fig. 2 is an end elevational view of the tattoo marker and the impervious pad associated therewith.

Referring more particularly to the accompanying drawings, 3 designates a metal

handle provided with a stamping block 4 which may be integral with the metal handle 3. The stamping block 4 is provided with a rectangular flat surface 5. The handle 3 and stamping block 4 may be made of iron or steel, nickel-plated, or chromium-plated, or such handle and stamping block may be made of other rust-resisting material.

Cast into the stamping block when the latter is formed, are a plurality of cylindrical tattoo markers 6 and for this purpose each of the cylindrical markers may be provided with a notch 7 near its lower end, as shown in Fig. 1, so that the metal of the block 4 may seat itself in such notches 7 and lock the markers 6 permanently in place and rigidly connected to the block 4 so as to virtually become a part thereof.

The markers 6 when cast into the block 4 are arranged in the form of letters, numerals, or other identification marks. The identification mark illustrated in Fig. 2 is B27, but, of course, the user of the tattoo marker illustrated in the drawings may be provided with any arrangement desired, but each hand stamp is permanently provided with a definite and predetermined set of identification marks which always remain in permanent and rigid connection with the stamping block.

The markers 6 may be made of tool steel and plated to resist rust. The marking points 8 are designed so as to be sufficiently sharp to easily penetrate the skin of the poultry or animals sufficiently deep to effect proper tattoo marking, but the conical surfaces 9 are so sloped as to be sufficiently blunt to prevent blemishing of the flesh or injury to the bird or animal. For this purpose it is preferred to have the angle between the horizontal plane extending through the base of the cone and the sloping side of the cone equal to approximately 52° or the angle between the sloping side of the cone and the vertical axis of the cone equal to approximately 38°.

A resilient pad 10, preferably of rubber or

other material impervious to the tattooing ink, is provided of a size to fit the rectangular surface 5 of the stamping block 4 and may be placed in the position shown in Fig. 1 by 5 pressing a blank pad 10 onto the points 8 so that the rubber will be penetrated and permitted to slip over the cylindrical pins 6 to the seat 5. It should be particularly noted that the pad 10 should not be of material 10 which would absorb the tattoo ink, because it is desired that the ink shall remain on the pins 6 which project from the pad 10. In other words, by reason of the pad 10 being impervious to the ink, the latter will not be 15 drawn away from the points 8, but will permit to flow by gravity the ink from the pad surface to the points 8 when the stamp is held vertical. The pad 10 may be of various thicknesses and may be readily removed and 20 renewed. The pad may be used to regulate the distance of penetration by contacting with the skin which yields to pressure. The pad 10 therefore also keeps the hard metal stamping block from coming in contact with 25 the skin of the bird or animal when the tattoo marker is used. The thickness of the pad 10 will therefore depend upon the particular use to which the tattoo marker shown is to be applied.

20 It should be particularly understood, however, that while the marking points 8 are sharp and of tool steel, the conical surfaces 30 9 are comparatively blunt so that the points 8 will penetrate only through the epidermis or outer layer of the skin so that the ink will 35 be carried under the skin and becomes indelibly imbedded therein, but the points do not enter the muscles or flesh of the bird or animal. The handle 3, the block 4, and the pins 6 40 being all substantially one rigid structure, cannot come apart or become broken and being in the hand stamp form the device is very easy to operate with accurate regulation of the pressure which is just sufficient to effect 45 proper identification of the property without causing any injury thereto.

The ink may be in the form of a stick of Chinese tattoo ink which is harmless, but permanent. A few drops of water may be placed 50 in a clean saucer and the stick-ink rubbed on the saucer to help dissolve it, using just enough of the stick-ink to make a good black mixture. This mixture is then applied by means of a brush to the points 8, the conical 55 surfaces 9 and those portions of the pins 6 which project from the pad 10 with a sufficient amount on the pad 10 adjacent the pins 6 to serve as a partial reservoir for the tattoo ink to flow from to the points 8 during continued use of the marker.

The tattoo marker may be used on any part 60 of the body of the bird or animal, but it is especially easy to use the marker under the wings of chickens or other poultry, in the 65 web or feet of ducks and geese, and in the

ears of rabbits, foxes, cattle, swine, sheep, dogs, etc. After the tattooing has been effected by means of the tattoo marker some additional stick-ink mixture may be applied to the punctured holes and rubbed into the 70 same and subsequently a damp clean sponge used to wash off the surface of ink-fluid.

It should also be particularly noted that it is important to avoid frightening the birds or animals, as well as to avoid injuring them. 75 No levers of any kind are used in the tattoo marker tending to multiply the pressure applied and applying such pressure too suddenly, but the simple hand stamp form shown in the accompanying drawings assures the 80 easy handling of the tattoo marked with an initial gentle pressure, slowly and gradually increased until sufficient to puncture to the required and desired extent, thereby enabling the operator of the tattoo marker to more 85 easily handle the poultry or animals while calm and relaxed.

Obviously those skilled in the art may make various changes in the details and arrangement of parts without departing from the spirit and scope of the invention as defined by the claims hereto appended and I wish therefore not to be restricted to the precise construction herein disclosed.

Having thus fully disclosed an embodiment 95 of my invention, what I desire to secure by Letters Patent of the United States is:

1. In a tattoo marker, the combination with a stamping block, of a handle therefor, a plurality of spaced-apart tattoo markers 100 cast rigidly with said block for permanent rigid connection thereto, and interlocking means between said markers and block to prevent substantial movement of the markers relative to said block in the event that the 105 markers become loose in their mounting.

2. In a tattoo marker, the combination with a holder, of a plurality of cylindrical tattoo pins, and points on said pins formed by conical extensions of said pins with the 110 sloping surfaces of the cones approximately at 52° with the plane of the base of the cone.

3. In a tattoo marker, the combination with a holder, of a plurality of spaced-apart tattoo markers carried thereby, and a pad 115 of resilient material impervious to the tattoo ink and fitting over said markers with the latter projecting therefrom.

4. In a tattoo marker, the combination with a stamping block having a seat, of a 120 handle for said block, a plurality of pointed tattoo markers having notches in their end portions remote from the points and cast into said block for rigid connection therewith, and a rubber pad perforated by said markers and fitting over the same against said seat.

5. A tattoo marker comprising a stamping block, a plurality of tattoo markers cast rigidly with said block, and interlocking means between said markers and block to prevent 130

substantial movement of the markers relative to said block in the event that said markers become loose in their mounting.

6. A tattoo marker comprising a marker, a plurality of tattoo markers carried thereby, and a pad of material impervious to the tattoo ink and fitting over said markers with said markers projecting therefrom.

In testimony whereof I have signed my name to this specification on this 18th day of September, A. D. 1928.

HARVEY J. DIVEKEY.
